UNITED STATES PATENT OFFICE.

PHILLIP SIMLER, OF ALLENVILLE, MISSOURI.

ATTACHMENT FOR RAILROAD-TIES.

SPECIFICATION forming part of Letters Patent No. 374,090, dated November 29, 1887.

Application filed October 6, 1887. Serial No. 251,633. (No model.)

To all whom it may concern:

Be it known that I, PHILLIP SIMLER, a citizen of the United States of America, residing at Alenville, in the county of Cape Girardeau and 5 State of Missouri, have invented certain new and useful Improvements in Railroad-Ties; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to certain new and useful improvements in attachments for railroad-ties, whereby the ties may be securely held in position in such localities where the road-bed is liable to be washed away; and my invention 20 consists in providing supports adjacent to the ties at suitable intervals, which are driven into the solid ground upon which the made road-bed rests, and connecting the ties to said piles or supports by straps or bars, so as to hold 25 them securely in place, as will be hereinafter fully set forth, and specifically pointed out in the claim.

In the accompanying drawings, which illustrate my invention, Figure 1 is a perspective 30 view showing my improvement applied, and Fig. 2 is an end view.

A refers to the ties, upon which the rails are placed and secured in the usual manner.

B represents the made ground upon which 35 the ties are placed, beneath which is the solid natural foundation, into which piles or posts C

are driven or otherwise planted, so as to be held securely and rigidly in position, the upper ends of these piles or posts extending a slight distance above the ground, and to the 40 ends thereof are bolted or otherwise attached metallic bars or straps D, the opposite ends thereof being bolted to the ties. The bars or straps D incline preferably from the posts upwardly to the ties, as shown. 45

In practice this device will be used on every fifth or sixth tie, or at farther or closer distances, as may be desired.

By means of the device hereinbefore described the ties are held securely in position, and should the made ground be washed away by floods or freshets the ties to which my improvement is applied will be held securely in position and the track will hold the intervening ones in place, so that when the made 55 ground of the road-bed is washed away it can be readily replaced without tearing up or re-laying the tracks.

I claim—

In combination with a railroad-tie, posts C 60 and straps or bars D, connecting the ties thereto, substantially as shown, and for the purpose set forth.

In testimony whereof I affix my signature in presence of witnesses.

PHILLIP ^{his} SIMLER.
mark.
